UNITED STATES PATENT OFFICE.

SIMON FRIEDBERGER, OF PHILADELPHIA, PENNSYLVANIA.

KNITTED FABRIC.

1,050,120.

Specification of Letters Patent. Patented Jan. 14, 1913.

Application filed March 21, 1912. Serial No. 685,212.

To all whom it may concern:

Be it known that I, SIMON FRIEDBERGER, a citizen of the United States, residing at Philadelphia, county of Philadelphia, and 5 State of Pennsylvania, have invented a new and useful Improvement in Knitted Fabrics, of which the following is a full, clear, and exact description, reference being had to the accompanying drawings, which form a part 10 of this specification.

The object of my invention is to produce a fabric adapted especially for use in making laundry bags and analogous knitted articles. In such articles it is highly desirable 15 that the fabric of which it is composed shall not unravel as a result of the rough handling to which it is exposed. It is also desirable that the fabric shall be of such elasticity that when exposed to pulling 20 stresses in different directions, it will give in different directions to a substantially uniform extent.

In the drawings: Figure 1 is a plan view of the fabric as it appears to the eye; Fig. 25 2 is a detail view of the fabric on an enlarged scale.

The fabric, which is intended to be manufactured on the ordinary traverse warp machine, is composed of three sets of threads, 30 two filling warp threads and one binding warp thread. The two sets of filler threads are marked respectively a , a' , a^2 , etc. and b , b' , b^2 , while the binder threads are marked c , c' , c^2 , c^3 etc.

35 It will be observed that the finished fabric, generally speaking, comprises longitudinal bars x , x' , x^2 , x^3 , etc. of interlooped threads composed of all three sets of threads, and transverse bars y , y' , y^2 , y^3 , etc. of floating threads composed of the two sets of filler warps. More specifically it will be observed 40 that the filler thread a (starting, say from point m) extends transversely in one direction to the longitudinal bar x thence directly 45 forward between adjacent intersections of the longitudinal bar x and the transverse bars y and y' , thence transversely in the opposite direction to the adjacent longitudinal bar x' , thence is formed into a loop at the 50 intersection of longitudinal bar x' and transverse bar y' , thence extends forward, in the course of which it is reversely curved upon itself, to the intersection of bars x' and y^2 , and thence transversely toward longitudinal bar x . Following the filler thread b from 55 the same point m , it will be observed that

it extends transversely in one direction to the longitudinal bar x , thence is formed into a loop at the intersection of longitudinal bar x and transverse bar y , thence extends forward, in the course of which it is reversely curved upon itself, to the intersection of bars x and y' , thence transversely in the opposite direction to the longitudinal bar x' , thence directly forward between adjacent intersections of the longitudinal bar x and the transverse bars y' and y^2 , and thence transversely toward longitudinal bar x .

Following the binder thread c' from the point n , the same extends forward through 60 the loop of the thread b' at the intersection of bars x' and y , thence forward under thread b and thread a , thence through one pocket of the reversely curved portion of thread b' , thence back over the neck of said 65 loop of thread b' , thence forward successively over thread b' and under thread a' and through the loop of thread a at the intersection of bars x' and y' , thence back 70 successively over and under thread b' and through the other pocket of the reversely curved portion of thread b' , thence again 75 through said loop of thread a , thence forward under threads a' and b' , thence through one pocket of the reversely curved 80 portion of thread a , thence back over the neck of said loop of thread a , thence forward successively over thread a and under thread b and through the loop of thread b' at the intersection of bars x' and y^2 , thence 85 back successively over and under thread a and through the other pocket of the reversely curved portion of thread a .

From the foregoing description it will be understood that the threads are so looped 90 together that if any one thread should be broken or cut at any point, any attempt, by pulling the loose end, to unravel the fabric, would result in tying a knot or knots in the threads and thus even more securely 95 securing the several threads together.

Having now fully described my invention, what I claim and desire to protect by Letters Patent is:

1. A knitted fabric composed of filler 105 warp threads each extending successively transversely and forwardly, throughout the length of the fabric, each of said threads, in its alternate forward extensions, being successively formed into a loop and reversely 110 curved, and a binder warp thread extending through and around the necks of the

loops, and through the pockets of said reversely curved portions, of the filler warp threads, substantially as described.

2. A knitted fabric composed of two sets of filler warp threads and a set of binder warp threads, said filler warp threads extending successively transversely and forwardly and each filler warp thread, in its alternate forward extension, being successively looped and reversely curved; each binder warp thread extending through and around the necks of the loops, and through the pockets of said reversely curved portions, of the filler warp threads, and in so extending forming loops binding together adjacent loops and pockets formed by the filler warp threads.

3. A knitted fabric composed of longitudinal chains composed of a set of binding warp threads and two sets of filler warp

threads, and transverse bars composed of said two sets of filler warp threads, each of said filler warp threads being looped and reversely curved in the formation of said chain, and each of said binder warps extending along one chain only and in so extending passing through the loops, and the pockets of the reversely curved portion, of the filler warp threads, and binding together the loops and pockets of the same, and also the loops and pockets of different filler and warp threads, substantially as described.

In testimony of which invention, I have hereunto set my hand, at Philadelphia, on this 11th day of March, 1912.

SIMON FRIEDBERGER.
